LADY'S HAND BAG

Morris Wunthal, New York, N. Y.

Application October 29, 1934, Serial No. 750,397

6 Claims. (Cl. 150—34)

This invention relates to receptacles, such as ladies' handbags, pocketbooks, and similar articles, and more particularly to combination handbags and toilet cases, such as vanity cases and cosmetic containers.

One object of this invention is to provide a combination handbag and toilet case in which the toilet case constitutes a fastener element of the bag.

Another object of the invention is to provide a combined toilet case and bag fastener construction which may be utilized in handbags of different types.

The above objects of the invention and other objects ancillary thereto will best be understood from the following description considered in connection with the accompanying drawing.

In the drawing:

Fig. 1 is a perspective view of a combination handbag and vanity case, showing the latter in projected position;

Fig. 1a is a perspective view showing the vanity case in retracted position;

Fig. 2 is a fragmentary section on the line 2—2 of Fig. 1a;

Fig. 3 is a fragmentary view partly in elevation and partly in section on the line 3—3 of Fig. 1a;

Fig. 4 is a section on the line 4—4 of Fig. 1, showing the vanity case in retracted position;

Fig. 5 is an end view of a combination bag of the U-shaped hinged metal frame type and a vanity case;

Fig. 6 is a fragmentary top plan view of a combination bag of the U-shaped hinged metal frame type and a cosmetic or lip-stick container;

Fig. 7 is a fragmentary section on the line 7—7 of Fig. 6; and

Fig. 8 is a similar section on the line 8—8 of Fig. 6.

Referring first to Figs. 1 to 4 of the drawing, the handbag 10 may be made of any suitable material, such as leather or fabric, and comprises a rear wall 12, a front wall 14 which is usually integral with the said rear wall, end gussets 16 stitched to the ends of said walls, and a closure flap 18 which may be integral with the rear wall 12 or in the form of a separate piece stitched to the upper edge of said rear wall. On the closure wall or flap 18 there is slidably mounted, as hereinafter more specifically described, a metal vanity case 20 for releasable engagement with a keeper 22 secured to the front wall 14 and extending through an opening 24 in the closure flap 18.

The vanity case comprises a box 26 within which a cake of powder or a cake of rouge, or both, may be contained together with a powder puff, and a cover 28 hinged to the box may contain a mirror 30. The box and cover are provided with interengaging fastening projections 32 and 34 for releasably securing the cover in closed

position. As shown in Fig. 1a, in the normal vertical position of the handbag, when the vanity case is disengaged from the keeper 22, and when the cover is opened the latter hangs from the lower hinge-edge 36, exposing the contents of the box and the mirror 30 for convenient use of the vanity case.

For slidably mounting the vanity case 20 on the handbag there are provided a guide member 36 secured to the flap 18 and a guide plate 38 secured to the bottom of the vanity case in any suitable way, as by rivets (not shown). The guide member 36 is secured to the flap 18 by a metal fastener plate 37 which is soldered or otherwise fixedly attached thereto. The plate 37 is provided with prongs 39 which are passed through the flap 18 and through apertures in a metal plate 41, positioned between the flap 18 and the lining 19, and clinched over the plate 41, as shown more clearly in Fig. 3. The fastener plate 37 also spaces the plate 38 to some extent from the flap 18, as shown in Fig. 4. The plate 38 has inturned flanges 40 for slidable engagement with the end portions of the member 36 and said flanges are reduced in width at their ends 42 for limiting the movement of the plate with respect to the guide member 36. The flange portions 42 of reduced width also provide greater clearance between the plate 38 and the flap 18 thereby to prevent said plate from engaging the flap 18 in the edge thereof at the opening 24 which might otherwise occur when sliding the vanity case from closure-releasing or retracted position shown in Fig. 4 to projected and closure-fastening or keeper-engaging position shown in Fig. 1.

As shown more clearly in Figs. 2 and 4, the keeper 22 is constituted by a U-shaped metal strap having a front longitudinal portion 44, which may be suitably ornamented if desired, and lateral portions 46 of a length sufficient to space said front portion from the flap 18 to permit the vanity case to slidably engage said front portion with a rather snug fit to prevent unintentional or accidental release of the vanity case from the keeper. For a more positive connection between the vanity case and the keeper, the portion 44 of the latter is provided with rounded projections or pimples 48 for engagement with rounded recesses or dimples 50 in the cover 28 of the vanity case. The keeper is secured to the front 14 of the handbag by prongs 52 integral with the lateral portions 46 but of reduced width. Said prongs pass through slits in the wall 14 and through slits in a metal plate 56, located between said wall and the lining 58, and are clinched over said plate, thus holding the keeper in fixed position on the wall 14 in forwardly projecting relation thereto. As the ends of the lateral portions 44 adjacent the prongs 52 are wider than the prongs, the keeper 22 is rigid with the plate 56 and the por-

tion of the wall 14 clamped between said plate and the ends of said lateral portions. The guide member 36 is similarly rigid with the plate 41 and the portion of the cover flap clamped between said guide plate and the fastener plate 37.

In Fig. 5, the invention is shown in connection with a handbag 60 of the well known hinged U-shaped metal frame type. As here shown, the keeper 62, which is of the same construction as the keeper 22, is secured to one wall 64 of the bag and projects forwardly through an opening 66 in the other wall 68, and the vanity case 70, which is of the same construction as the vanity case 20, is slidably mounted on the wall 68 for releasable engagement with the keeper. The keeper 62 and the vanity case 70 can be secured to the walls 64 and 68 in substantially the same way as the keeper 22 and vanity case 20 are secured to the wall 14 and flap 18 in the construction shown in Figs. 1 to 4 described above.

In Figs. 6 to 8 there is illustrated a combination handbag and lip-stick container. The handbag 72 is of the type shown in Fig. 5 and comprises a hinged metal frame constituted by two U-shaped metal members 73 and 74 hinged together in the well known way (not shown), the fabric or leather material of the bag walls 75 and 76 being secured to said frame members in the usual way. A metal keeper 77 is secured to the top of metal frame 73 of the wall 75 and projects laterally over the metal frame 74 of the wall 76. The projecting portion 78 of the keeper 77 is provided with a cylindrical bore 79. A metal bracket 80 provided with a cylindrical bore 81 is secured to the frame member 74. The keeper 78 and the bracket 80 may be secured to the metal frames 73 and 74 in any suitable way as, for example, by being soldered thereto. When the bag is closed, as shown in Fig. 6, the bores 78 and 81 are in alignment. A vanity case here shown as a lip-stick or other cosmetic container or case 82 of cylindrical form is slidably mounted in the bore 81 of bracket 80, preferably with a snug fit, and may be projected into the bore 79 of the keeper 77 to releasably secure the bag in closed position. To open the bag the case 82 is withdrawn from the bore 79 to retracted position. The case 82 is provided with an enlarged closure cap 83 which affords a convenient finger grip for moving the case to projected and retracted positions. Said cap 83 may carry a lip-stick and hence is removable but is releasably secured to the case in any suitable way to prevent its removal, especially when operating the case into and out of engagement with the keeper 77.

From the foregoing description it is seen that each of the embodiments illustrated on the accompanying drawing is well adapted to fulfill the objects of the present invention, as each embodiment comprises a combination receptacle including a lady's handbag and vanity case in which the vanity case may constitute a fastener element for the bag. In the constructions shown in Figs. 1 to 5, the cover of the vanity is engaged by the keeper when the latter is in projected position whereby said cover is prevented from being opened until the vanity case is moved to retracted position out of engagement with the keeper.

While I have shown and described several embodiments of this invention, it will be understood that the latter is capable of other specific embodiments and it will be understood that each of the embodiments here shown may be altered in construction. Therefore, I do not wish to be limited to the precise constructions shown except as may

be required by the appended claims considered in connection with the prior art.

Having thus described my invention what I claim and desire to secure by Letters Patent of the United States is:

1. A receptacle comprising a plurality of relatively movable walls, a keeper secured to one of said walls and projecting laterally with respect to another of said walls, said keeper having an opening therein, and a case slidably mounted on said last mentioned wall and movable into projected position in said opening in the keeper for releasably securing said walls in closed position, said case having a cover which engages said keeper when the case is moved to projected position whereby opening of said cover is prevented until the case is moved out of said opening to retracted position.

2. A receptacle comprising two walls, a closure flap extending from one of said walls and overlying the other of said walls, said flap having an opening therethrough, a U-shaped strap secured to the last mentioned wall and projecting through the opening in said flap, a guide member mounted on said flap and a vanity case slidably mounted on said member for movement to projected position in engagement with said U-shaped strap to secure said flap in closed position, and to retracted position out of engagement with said U-shaped strap to release said flap.

3. A receptacle comprising a lady's handbag having two walls, a closure flap extending from one of said walls in overlying relation to the other of said walls and provided with an opening therethrough, a guide member mounted on said flap, a vanity case having a plate slidably engaging said member, and a keeper secured to one of said walls and projecting through the opening in said flap when the latter is in closed position, said keeper having a front portion adapted to be engaged by said vanity case for releasably securing said flap in closed position.

4. A combination receptacle comprising a lady's handbag, a vanity case movably mounted on said bag and a keeper adapted to be releasably engaged by said vanity case for releasably closing said bag, said vanity case having a movable cover held in closed position by said keeper and thereby prevented from being opened when said keeper is engaged by said vanity case.

5. A combination receptacle comprising a lady's handbag, a vanity case mounted on said bag, and a U-shaped strap, said vanity case and U-shaped strap being relatively movable into and out of engagement with each other for releasably holding the bag closed, said vanity case having a movable cover held in closed position by said strap when said case and strap are in engagement whereby to prevent said cover from being opened until said vanity case and said strap are disengaged from each other.

6. A combination receptacle comprising a lady's handbag having two U-shaped frame members hinged together, bag walls secured to said frame members, one of said walls having an opening therethrough, a keeper secured to the other of said walls internally of the bag and projecting through said opening, and a vanity case secured externally of the bag to the wall provided with said opening and adapted to engage said keeper when the latter is projected through said opening, said vanity case having a movable cover which is held in place by said keeper.
